UNITED STATES PATENT OFFICE.

GEORGE D. HAINES, OF CHICAGO, ILLINOIS, ASSIGNOR TO VAUGHAN & BUSHNELL MANUFACTURING COMPANY, OF CHICAGO, ILLINOIS, A CORPORATION OF ILLINOIS.

MANUFACTURE OF CARPENTER'S PLANES.

Application filed July 14, 1924. Serial No. 725,837.

To all whom it may concern:

Be it known that I, GEORGE D. HAINES, a citizen of the United States, and a resident of Chicago, in the county of Cook and 5 State of Illinois, have invented certain new and useful Improvements in Manufacture of Carpenters' Planes, of which the following is a full, clear, and exact description.

The invention relates to the manufacture 10 of carpenters' planes and its primary object is to provide a method of forging the plane bodies.

Heretofore, it has been the general practice to cast plane-bodies of this type. In 15 the use of carpenters' planes, it frequently occurs that they are dropped from a work-bench or from one floor of a building to another while the building is in the course of construction. Cast bodies are so readily breakable that, in most cases, such dropping resulted in rendering the body useless. 20 This objection to the use of cast bodies has been recognized in the art.

The present invention overcomes this objection by providing a practical method of 25 forging the bodies so as to render them substantially unbreakable.

A further object of the invention is to 30 provide an improved method of forging plane-bodies of this type which can be practiced without prohibitive cost in the production of the bodies, resulting from wear upon and breakage of dies, and by which 35 plane-bodies of uniform quality will be produced.

The invention consists in the several novel 40 features hereinafter set forth and more particularly defined by claims at the conclusion hereof.

In the drawings: Fig. 1 is a perspective 45 of a bar from which a number of bodies are successively forged. Figs. 2 and 3 are respectively a plan and side elevation, showing the first step in the forging operation to shape the metal for effective distribution to form the several parts of the plane-body. Fig. 4 is a plan, showing the result of the next step in the forging operation. Fig. 5 is a side elevation, Fig. 6 a longitudinal 50 section on line 6—6, and Fig. 7 a transverse section on line 7—7 of the metal when it has been shaped, as shown in Fig. 4. Fig. 8 is a plan of the partially formed body after the next step or shearing operation

of the method has been performed. Fig. 9 55 is a transverse section, showing the shearing operation. Fig. 10 is a cross-section, showing the next step of the method, which consists in bending the outer side portions of the metal upwardly or substantially at 60 right angles to the sole of the body. Fig. 11 is a longitudinal section and Fig. 12 a transverse section of the body after the bending operation shown in Fig. 10 has 65 been performed. Fig. 13 is a section, illustrating the next step in the method, which consists in shaping the metal in a finishing die to give it, as nearly as possible, the correct shape desired. Fig. 14 is a perspective, 70 showing the finished plane-body.

The plane-bodies are forged from a bar A of metal. In practice, these bars are preferably of sufficient length so that a series of bodies may be successively formed therefrom. In the manufacture of the bodies, one end of the bar A is heated so that it can be forged. Next, the heated end is forged into a block or blank approximately of the shape shown at A' in Figs. 1 and 2, to densify the metal and to distribute it so that it can be readily forged to form all of the integral parts of the plane-body. The greater portion of the metal is disposed at the longitudinal center where it is necessary to form the medial portions 85 of the side flanges of the body and the frog-base on the top of the plane-bottom and between the side-flanges. This shaping is effected by hammering the metal between suitably shaped dies, which will, in one or 90 two blows, forge the metal into substantially the shape shown.

Next, the portion A' of the bar, while it is still hot, is hammered or drop-forged between B, B' which are adapted to shape the metal into a blank B² of substantially the form shown in Figs. 4, 5, 6 and 7. Usually four or five blows are sufficient to give this formation to the metal. During this operation, the metal will be forged and shaped to simultaneously form the bottom or sole 15 of the plane-body; the boss 16 on the upper face of the sole which forms a seat for the knob 30; an upstanding lug 17 on the boss for connection with a screw for holding a front knob 30 on the plane; a frog-base on the upper face of the sole consisting of inclined ribs 19, lugs 20 for the screws for 165

holding the frog on the base and a lug 21 for a frog-adjusting screw; a reinforcing cross-rib 22 on the upper face of the sole; a lug 23 for a screw to secure a handle 31; 5 and a point 25 on the upper face of the sole for holding the handle against horizontal rotation. During the same operation, the metal at the side of the sole is shaped into upwardly extending portions 26, approximately to the height or a little above the top 10 of cross-rib 22 and the top of ribs 19, and laterally extending marginal portions 27. The dies B, B' for this operation are shaped to form the side-flanges of the body of some- 15 what less thickness than the sole, so that the metal can be more readily shaped and so that the portions 27 will be of the necessary thickness and outline to form the upper portion of the side flanges. During this opera- 20 tion, the laterally extending portions 27 will be densified so they can be bent into alignment with and form continuations of the portions 26, without danger of rupturing the metal in bending. These dies are also shaped 25 so that the central portions 27' of the side flanges, when bent into final shape, will extend upwardly above the frog-base sufficiently to cover the lower portions of the knife and frog so their end-portions will be 30 curved or sloped, as at 27^a, from the high marginal portions 27' to the ends of the sole of the body. During this operation, the metal in the sole is also forged to leave a thin transverse web of metal 15' where the 35 knife-slot is to be formed in the sole. The block A' contains an excess of metal to insure substantially uniform densification of all portions of the body while it is being forged and the formation of all parts there- 40 of. The excess of metal is forced laterally from the margins of the blank B² and be- 45 tween the dies B, B', as at 28.

Next, the partially forged body is placed 45 between dies C, C' which shear or trim the excess metal from the blank B², so that, when the side-flanges are completely formed, they will be substantially of the correct shape.

Next, the partially sheared blank B², 50 while it is still hot, is placed between bending dies D, D', which are then operated and force or bend the laterally extending portions 27 upwardly so they will be aligned with the portions 26 to form complete side 55 flanges. This manner of forming the side flanges, by first simultaneously forging the blank A' to shape the sole and lower and central portions of the side-flanges at right-angles to the sole, with laterally extending 60 portions which are bendable for alignment with the lower portions, has been found to be practically possible without undue stresses on the dies or resulting in their breakage.

65 Next, the body, if desired or necessary, is

pressed between finishing dies E, E', which finally force the several parts into the substantially correct shape and rectify any irregularities or variations which may occur in the forging of and bending steps. 70

All of the forging and shaping operations are usually performed while the blank remains attached to the unused portion of the bar A for convenience in handling the blanks or shifting them from one set of dies 75 to the next. After the final shaping operation in dies E, E', the body is sheared from the bar. All of these steps are performed in such rapid succession that the reheating 80 of the blank will be avoided.

Next, the outer faces of the side flanges and the bottom face of the sole 15 are planed; next, the web of metal 15' is removed by reaming and broaching, so as to form a knife-slot 15^a in the sole, and lugs 17, 23, 85 20 and 21 are drilled and tapped for the screws which they are to receive. The body is then ready for assembling of the knob 30, handle 31, and for the attachment of the frog 32, to which the knives are adjustably 90 connected in the usual manner.

The invention exemplifies a method of forging carpenters' hand-plane-bodies, so that they will be substantially unbreakable 95 in use and one which can be practiced commercially without undue cost or loss resulting from die-breakage. The invention has been practiced to produce commercial drop-forged plane-bodies, which have successfully overcome plane-breakage in a plane-body 100 in which the sole, side-flanges, frog-base and handle and knob-attaching lugs are integral.

The invention is not to be understood as restricted to the details set forth, since these 105 may be modified within the scope of the appended claims, without departing from the spirit and scope of the invention.

Having thus described the invention, what I claim as new and desire to secure by Letters Patent, is:

1. That improvement in the manufacture of plane-bodies comprising a substantially flat sole or bottom, side flanges and attaching lugs, which consists in forging a bar of metal into a blank shaped to form the sole of the plane with integral attaching lugs on one face thereof and laterally extending portions, then bending only the laterally extending portions at an angle to the sole to extend upwardly therefrom to form the plane-sides, and then finishing the blank to form the plane-body. 115

2. That improvement in the manufacture of plane-bodies comprising a substantially flat sole or bottom with side flanges and attaching lugs, which consists in forging a bar of metal into a blank shaped to form the sole of the plane with integral attaching lugs on one face thereof and laterally extending portions with an excess of metal on 120 125 130

the margins of the laterally extending portions, then shearing the margins conformably to the desired upper edges of the side flanges, then bending only the laterally extending portions at an angle to the sole to extend upwardly therefrom to form the plane-sides, and then finishing the blank to form the plane-body.

3. That improvement in the manufacture of plane-bodies comprising a substantially flat sole or bottom with side flanges and attaching lugs, which consists in forging a bar of metal into a blank shaped to form the sole with integral attaching lugs on one face thereof and with laterally extending portions, then bending only the laterally extending portions at an angle to the sole to extend upwardly therefrom to form the plane-sides, then shaping the blank in finishing dies, and then machining the blank to form the finished plane-body.

4. That improvement in the manufacture of plane-bodies comprising a substantially flat sole or bottom with side flanges and attaching lugs, which consists in forging a bar of metal into a blank shaped to form the sole with integral attaching lugs on one face thereof and with laterally extending portions, with an excess of metal around the margins of the laterally extending portions, then shearing the margins conformably to the upper edges of the finished side-flanges, then bending only the laterally extending portions at an angle to the sole to extend upwardly therefrom to form the plane-sides, then shaping the blank in finishing dies, and then machining the bent blank to form the finished plane-body.

5. That improvement in the manufacture of plane-bodies comprising a substantially flat sole or bottom with side flanges and attaching lugs, which consists in forging a bar of metal to bring a greater portion of metal adjacent its longitudinal center, then forging it into a blank shaped to form the sole of the plane with whole attaching lugs on one face thereof and with laterally extending portions, then bending the laterally extending portions at substantially right angles to the sole, and then machining the blank to form a finished plane-body.

6. That improvement in the manufacture of plane-bodies comprising a substantially flat sole or bottom with side flanges and attaching lugs, which consists in forging a bar of metal to bring a greater portion of metal adjacent its longitudinal center, then forging it into a blank shaped to form the sole with whole attaching lugs on one face thereof and laterally extending portions, and an excess of metal around the margins of said portions, then shearing the margins of the laterally extending portions conformably to the desired upper edges of the side flanges of the body, then bending the later-

ally extending portions at substantially right angles to the sole, and then machining the blank to form a finished plane-body.

7. That improvement in the manufacture of plane-bodies comprising a substantially flat sole or bottom with side flanges and attaching lugs, which consists in forging a bar of metal to bring a greater portion of metal adjacent its longitudinal center, then forging it into a blank shaped to form the sole with whole attaching lugs on one face thereof and laterally extending portions, then bending the laterally extending portions at substantially right angles to the sole, then shaping the bent blank in a finishing die, and then machining the blank to form a finished plane-body.

8. That improvement in the manufacture of plane-bodies comprising a substantially flat sole or bottom with side flanges and attaching lugs, which consists in forging a bar of metal to bring a greater portion of metal adjacent its longitudinal center, then forging it into a blank shaped to form a substantially flat sole of the plane with whole attaching lugs on one face thereof, and laterally extending portions with an excess of metal around the margins of said portions, then shearing the margins of the laterally extending portions conformably to the upper edges of the side flanges of the body, then bending the laterally extending portions at substantially right angles to the sole, then shaping the bent blank in a finishing die, and then machining the blank to form a finished plane-body.

9. That improvement in the manufacture of plane-bodies comprising a substantially flat sole or bottom with integral side flanges and attaching lugs, which consists in simultaneously forging a bar into shape to form the sole with whole attaching lugs on one face thereof, angularly extending portions forming the lower portions of the side flanges and portions extending laterally from said angular portions adapted to form the upper portions of the side flanges, then bending only the laterally extending portions to bring them substantially into alignment with said angular portions to form complete side flanges, and then machining the blank to form a finished plane-body.

10. That improvement in the manufacture of plane-bodies comprising a substantially flat sole or bottom with integral side flanges and attaching lugs, which consists in forging a bar to bring a greater portion of metal adjacent its longitudinal center, then simultaneously forging it into shape to form the sole with whole attaching lugs on one face thereof, angularly extending portions forming the lower portions of the side flanges, and laterally extending portions adapted to form the upper portions of the side flanges, then bending only the laterally

extending portions to bring them substantially into alignment with said angular portions to form complete side-flanges, and then machining the blank to form a finished 5 plane-body.

11. That improvement in the manufacture of plane-bodies comprising a substantially flat sole or bottom with integral side-flanges and attaching lugs, which consists in forging 10 a bar to bring a greater portion of metal adjacent its longitudinal center, then simultaneously forging it into shape to form the sole with whole attaching lugs on one face thereof and with angularly extending portions forming the lower portions of the side-flanges, and portions extending laterally 15 from said angular portions adapted to form the upper portions of the side-flanges and an excess of metal around the margins of the laterally extending portions, then shearing 20 the blank conformably to the shape of the side-flanges, then bending only the laterally extending portions to bring them substantially into alignment with said angular portions to form complete side-flanges, then placing the bent blank into a finishing die, 25 and then machining the blank to form a finished plane-body.

12. That improvement in the manufacture 30 of plane-bodies comprising a substantially flat sole or bottom with integral side-flanges and attaching lugs, which consists in forging a blank into shape to form the sole with a whole frog-base on one face thereof, angularly extending portions forming the lower 35 portions of the side-flanges and with a whole cross-rib between said angularly extending portions, and portions extending laterally from the angular portions adapted to form 40 the upper portions of the side-flanges, then bending the laterally extending portions into alignment with said angular portions to form whole side-flanges, and then machining the blank to form a finished plane-body.
13. That improvement in the manufacture 45 of plane-bodies comprising a substantially flat sole or bottom with integral side-flanges and attaching lugs, which consists in simultaneously forging a blank into shape to form 50 the sole with the whole frog-base on one

face thereof and angularly extending portions forming the lower portions of the side-flanges, and portions extending laterally from the angular portions adapted to form the upper portions of the side-flanges and 55 disposed above the frog-base, then bending only the laterally extending portions into alignment with said angular portions to form whole side-flanges, and then machining the blank to form a finished plane-body. 60

14. That improvement in the manufacture of plane-bodies comprising a substantially flat sole or bottom with integral side flanges and attaching lugs, which consists in simultaneously forging a blank into shape to form 65 the sole with the frog-base on one face thereof, angularly extending portions forming the lower portions of the side-flanges united with sides of the frog-base, a complete cross-rib between said angularly extending portions, and outwardly extending portions adapted to form the upper portions of the side-flanges and above the cross-rib and frog-base, then bending only the outwardly extending portions into alignment with said 70 angular portions to form whole side-flanges, and then machining the blank to form a finished plane-body.

15. That improvement in the manufacture 75 of plane-bodies comprising a substantially flat sole or bottom with integral side flanges and attaching lugs, which consists in simultaneously forging a bar into shape to form the plane bottom with the attaching lugs on one face thereof, and a portion extending 80 crosswise of reduced thickness, angularly extending portions to form the lower portions of the side flanges, and laterally extending portions adapted to form the upper portions of the side flanges, then bending the laterally extending portions into alignment with said angular portions to completely form the side flanges, and then removing the portion of reduced thickness from the sole, and machining the blank to form a finished plane-body. 85

Signed at Chicago, Illinois, this 10th day of July, 1924.

GEORGE D. HAINES.
